CLAIM

The ornamental design for a lid for a computerized
electronic safe, as shown and described.

DESCRIPTION

FIG. 1 is a top perspective view of a lid for a computerized
electronic safe showing my new design;

FIG. 2 is a front elevational view thereof on a larger
scale than shown in FIG. 1;

FIG. 3 is a rear elevational view thereof, on a larger
scale than shown in FIG. 1; and

FIG. 4 is a right side elevational view thereof, on a
larger scale than shown in FIG. 1 the side opposite is
similar thereto.

The undisclosed bottom of the design is conventional
and unornamented.

FIG. 1

FIG. 2

FIG. 3

FIG. 4
